OPTICAL IMAGE SPLITTER

Bernard J. Lipari and Robert R. Hickerson, Overland Park, Kans., assignors to Beston Electronics, Inc., Prairie Village, Kans.

Filed July 9, 1969, Ser. No. 18,123

Term of patent 14 years

Int. Cl. D16—08

U.S. Cl. D61—1

Fig. 1.

Fig. 2.

Fig. 3.

Fig. 4.

FIG. 7.

FIG. 5.

FIG. 6.

FIG. 1 is a top, front perspective view of the optical image splitter showing our new design;

FIG. 2 is a top plan view thereof;

FIG. 3 is a front elevational view thereof;

FIG. 4 is a rear elevational view thereof;

FIG. 5 is a side elevational view thereof;

FIG. 6 is a side elevational view thereof showing the side opposite to that shown in FIG. 5; and

FIG. 7 is a bottom plan view thereof.

We claim:

The ornamental design for an optical image splitter, as shown.
